ROTARY TOOTHBRUSH

Arthur F. Pruner, Oklahoma City, Okla., Ibbie
 L. Pruner administratrix of the estate of said
 Arthur F. Pruner, deceased

Application December 10, 1938, Serial No. 244,912

2 Claims. (Cl. 15—27)

This invention relates to improvements in toothbrushes, and more particularly to toothbrushes in which the bristles are mounted in a wheel or rotor and are adapted to enter and remove foreign matter from between the interstices between the teeth as the brush is reciprocated horizontally.

The conventional toothbrush with fixed bristles can only be made to enter and clean the spaces between the teeth by moving the brush vertically, which, to the average individual, is either entirely too much trouble or is beyond the realm of his knowledge. As a consequence the conventional toothbrush used by the average individual does not properly clean between the teeth. When the fixed bristle brush is reciprocated horizontally over the teeth, the flexible bristles simply pass over the outer surface of the teeth and do not penetrate the interstices between the teeth.

The chief object of this invention, therefore, is to overcome the above mentioned difficulties, and to enable the average individual to properly clean his teeth as he moves his toothbrush horizontally across his teeth, which is the ordinary and most natural movement for brushing any article.

Another object of the invention is to provide a device of this class which is of simplified construction and embodies a rotatable bristled brush which is easily removable for cleaning or replacement.

A further object of my invention is to provide a toothbrush which not only is possessed of these special attributes, but which is also possessed of the usual attributes of simplicity, cheapness of manufacture and reliability.

The details in the construction of a preferred form of my invention, together with other objects attending its production, will be better understood from the following detailed description when read in connection with the accompanying drawing, which is chosen for illustrative purposes only, and in which,

Figure 1 illustrates the manner of holding and using my improved rotary brush;

Figure 2 is a view illustrating the manner in which the serrated surface of my rotary brush enters the spaces between the teeth adjacent the gums;

Figure 3 is a perspective view of a portion of the brush which I choose to call the brush head;

Figure 4 is a perspective view of the rotatable brush; and,

Figure 5 is a view of the assembled brush, cer-

tain parts being in section to illustrate certain preferred details of construction.

Like characters of reference designate like parts in all the figures.

As will be seen from the drawing, my toothbrush comprises three main elements, namely, a brush head which is designated as a whole by the numeral 6; a rotatable wheel-like brush, which is designated as a whole by the numeral 7; and a handle 8.

The brush head 6 includes a pair of substantially semi-circular parallel side walls 9 and 10 which are spaced apart by an integral peripheral wall 11. Each of the side walls 9 and 10 are preferably provided with aligned substantially semi-circular offset portions 12 and 13 which serve to rotatably receive the opposite ends of a bristle holding rotor 14, which will be hereinafter described.

Near their approximate center lines the side walls 9 and 10 are provided with aligned opposite axle sockets 15 and 16 which serve to journal the opposite ends of an axle 17 on which the rotor 14 is mounted.

The peripheral wall 11 of the brush head is provided with a threaded lateral handle connection which is divided longitudinally into two semi-cylindrical portions 18 and 19, the base of each half of this connection being rigidly connected in any suitable manner to the peripheral wall near one of its ends. As a continuation of the division between the two handle connection parts 18 and 19, the peripheral wall 11 is slotted longitudinally to a point near its opposite end, the slot being designated by the numeral 22. This slot 22 permits the side walls 9 and 10 to be moved slightly apart to release the opposite ends of the brush axle 17 from their positions in the bearings 15 and 16, thus facilitating the removal of the brush 7 from the brush head, for cleaning or for replacement.

The brush 7 comprises a cylindrical rotor 14 in the peripheral surface of which are mounted a plurality of bristles extending radially outward therefrom. These bristles may be seated in rubber or in any other suitable material, or in other words the rotor 14 may be made of rubber, as shown, or of any other suitable material. The bristles of the brush 7 are graduated in length so as to form a serrated peripheral brushing surface. The serrated portions of the peripheral surface of this brush are alternately long and short as illustrated, the longer portions being designated by the numerals 20, while the shorter intermediate portions are designated by the numerals 21.

The rotor 14 is mounted on an axle 17, the ends of which project a short distance from either end of the rotor and are adapted to be journaled in the bearings 15 and 16 of the brush head. The 5 size of the brush head is, of course, sufficient to permit the free rotation of the brush 7 therein.

In assembling the toothbrush, after the brush 7 has been rotatably positioned between the side walls of the brush head 6, as just explained, the 10 two halves of the handle connection are manually pressed together and inserted into the threaded end of the handle 8 and the handle 8 is then screwed tightly on to the brush head. This handle 8 naturally holds the side walls 9 15 and 10 of the brush head rigidly positioned with relation to each other, which positioning naturally prevents the accidental or inadvertent removal of the brush 7 from the head.

As previously mentioned the toothbrush is 20 moved in horizontal manner back and forth across the teeth, the brush 7 being forced to rotate by its contact with the teeth. The long serrations 20 of the brush are preferably spaced apart a distance so that adjacent ones will enter 25 the interstices at the opposite sides of each tooth, while the short serrations 21 contact the outer surface of each tooth. The operation is repeated on the inside surface of the teeth. By placing the periphery of the brush 7 adjacent the gums 30 the long serrations 20 thoroughly clean the space between the teeth at the base of the teeth and also serve to massage the gums.

When it is desired to replace or clean the brush 7 the handle 8 is simply unscrewed from the 35 brush head 6, the side walls 9 and 10 of the brush head are sprung apart and the ends of the axle 17 are thus easily released from their bearings 15 and 16.

While I have described and illustrated a specific embodiment of my invention, I am aware that numerous alterations and changes may be made therein and I do not wish to be limited except by the prior art and by the scope of the 5 appended claims.

I claim:

1. As an article of manufacture, a toothbrush comprising: a hollow substantially semi-cylindrical brush head; a rotatable brush having a 10 serrated peripheral bristled surface journaled in side walls of said brush head, alternate ones of the serrated portions of said bristled surface being of greater length than the intermediate serrated portions thereof; and a handle removably attached to said brush head, the longitudinal axis of said handle being substantially at right angles to the axis of rotation of said brush. 15

2. As an article of manufacture, a toothbrush comprising: a hollow substantially semi-cylindrical brush head having two parallel semi-circular side walls spaced apart by an integral peripheral wall; a longitudinal slot in said peripheral wall extending from one of its ends to a point near its other end; a threaded substantially cylindrical 20 longitudinally bisected laterally projecting handle connection rigidly attached to said peripheral wall, the base of each portion being immediately adjacent the open end of the longitudinal slot in said peripheral wall; an elongated handle having a threaded bore in one of its ends, said bore adapted to receive said bisected laterally projecting handle connection; and a substantially wheel-like brush removably journaled for free 25 rotation between the side walls of said brush head. 30

ARTHUR F. PRUNER.
